UNITED STATES PATENT OFFICE.

TAUBE DAVIS, OF NEW YORK, N. Y., ASSIGNOR TO FRANKLIN SIMON & CO., INC., OF NEW YORK, N. Y., A CORPORATION OF NEW YORK.

DESIGN FOR A COAT.

Application filed January 16, 1926. Serial No. 16,131. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Coat, of which the following is a specification, reference being had to the accompanying drawing, forming part thereof, wherein—

The coat is distinguished by a substantially straight line effect with somewhat of a flaring bottom and an ornamental standing collar having a fur edging with ornamental stripes below the fur edging, the ornamental stripes matching in color and general appearance with ornamental members on the cuffs and on the two pockets positioned substantially in line with the lower part of the sleeves.

Figure 1 is a front view of a coat, illustrating my new design, the same being shown on a figure.

Figure 2 is a two-thirds side view of the coat shown in Figure 1, the same being illustrated on a figure.

Figure 3 is an enlarged elevation of the lower part of one of the sleeves, showing the ornamental arrangement of cuff and ornamental members positioned adjacent the cuff.

Figure 4 is an enlarged fragmentary view showing part of the coat with an enlarged view of the pocket and its ornamental facing.

I claim:

The ornamental design for a coat, substantially as shown and described.

TAUBE DAVIS.
